Primary Examiner — April Rivas*Assistant Examiner* — Tia Ruth-Renee Polidori(74) Attorney, Agent, or Firm — Johnston IP Law, PLLC(57) CLAIM

The ornamental design for a meat smoker firebox door as shown and described.

DESCRIPTION

FIG. 1 is a front perspective view of our new design for a meat smoker firebox door shown in an assembled, closed configuration with an environmental meat smoker;

FIG. 2 is a front elevation view thereof;

FIG. 3 is a rear elevation view thereof;

FIG. 4 is a right-side elevation view thereof;

FIG. 5 is a left side elevation view thereof;

FIG. 6 is a top plan view thereof;

FIG. 7 is a bottom plan view thereof;

FIG. 8 is a back elevation view of our new design for a meat smoker firebox door shown in isolation for clarity of disclosure; and,

FIG. 9 is a back perspective view thereof.

The portions of the meat smoker firebox door shown in broken line form no part of the claimed design. The broken line showing of a meat smoker in FIGS. 1-7 depicts environment and forms no part of the claimed design.

1 Claim, 9 Drawing Sheets(56)
